(57) **CLAIM**

The ornamental design for a C6 stage 2 waterfall console extension, as shown and described.

DESCRIPTION

FIG. 1 is a rear left perspective view of a C6 stage 2 waterfall console extension showing my new design;
FIG. 2 is a front right perspective view thereof;
FIG. 3 is a bottom right perspective view thereof;
FIG. 4 is a front elevational view thereof;
FIG. 5 is a rear view thereof; and,
FIG. 6 is a right side view thereof, the opposite side being a mirror image.
